 Claims priority, application Netherlands Nov. 28, 1959
 7 Claims. (Cl. 252—501)

This invention relates to a semi-conductor device, in particular a photosensitive device, having an activated semi-conductive and photo-conductive member respectively, and to methods of making same. Such activated semi-conductor members are used inter alia in photoelectric cells or in the photo-sensitive or electro-luminescent part of so-called electro-optical systems which comprise a combination of a photo-sensitive element and an electroluminescent element, for example a solid-state radiation intensifier, and the like, or also in electroluminescent elements, in which the activation may also determine the intensity and the spectral distribution of the photosensitivity and of the radiation emitted respectively.

Many materials which show photosensitive and/or electroluminescent properties are known, such for example as the sulphides, selenides or tellurides of, for example, bivalent or trivalent elements, or also elementary semi-conductors, such for example as selenium. Among the large group of photosensitive materials known per se, the semi-conductor compounds cadmium sulphide and cadmium selenide are to be preferred because they may have a particularly high photosensitivity and high dark resistance when activated suitably. In order to obtain a high photosensitivity in these compounds, it is necessary, however, to incorporate in these compounds a rather large quantity of activators, such for example as silver or copper, in a concentration of, for example, 10^{-4} — 10^{-3} activators per molecule of CdS. However, this is not possible as such; therefore, a corresponding quantity of so-called co-activator must be added simultaneously to the cadmium sulphide, for which are used in general trivalent metals, such for example as gallium or also the halogens. However, this co-activation is an extremely critical process since the quantities of activator and co-activator should be matched to each other very accurately. In the case of an excess of activator, this activator is not taken up in the right manner or incompletely in the crystal lattice and may cause there separation at the surface and formation of so-called killer centers which drastically decrease the photosensitivity, while in the case of an excess of co-activator the dark resistance deteriorates strongly. Since these compounds are hard to melt owing to their high melting temperature and decomposition by the volatility of the components sulphur and selenium, it is practically not possible, unless under conditions hard to maintain, to perform the incorporation of activators via the melt, for example simultaneously with the crystallization process for the formation of crystals. Analogous activation problems may present themselves in electroluminescent members, in which it may also be desirable that the relative member has a high resistance when activated effectively. A further drawback of cadmium sulphide and a photosensitive substance is that it is rather slow and more in particular has a decay time of the order of magnitude of approximately 0.1 sec.

One of the objects of the present invention is to provide a group of materials with a suitable activation in which the above drawbacks do not occur or at least to a far smaller extent.

The invention is based on the surprising observation that in the semi-conductor compounds of the composi-

tion AB_2X_4 , in which A represents one or more of the elements cadmium and zinc, B one or more of the elements In, Ga, Al, and X one or more of the elements S, Se and Te, the activation process can be carried out in an extremely simple manner when using certain activators, in which, thanks to a process of automatic co-activation by the compound itself, the co-activator may even be omitted, if desired. In addition, it has appeared that these compounds when activated suitably are also particularly suitable in other respects, in particular as photosensitive material.

In a semi-conductor device, in particular a photosensitive device having an activated semi-conductor and photosensitive member respectively, the semi-conductor member according to the invention comprises substantially a compound of the composition AB_2X_4 , in which A represents one or more of the elements Zn and Cd, B one or more of the elements In, Ga and Al, and X one or more of the elements S, Se or Te, which contains as activator at least one of the monovalent metals from the group Au, Ag, Cu.

Neutral elements or other activators may simultaneously be added to the semi-conductor member. It has appeared, however, that already particularly favourable results as far as the photosensitivity is concerned are obtained when the semi-conductor member comprises as activator only one or more of the monovalent metals Au, Ag and Cu. It has appeared possible in a simple and reproducible manner without the use of a co-activator to incorporate a satisfactorily operating atomic concentration of approximately 10^{-5} to approximately 10^{-2} of these activators. The atomic concentration of said activators preferably amounts to from 10^{-4} to 5×10^{-3} . The thus activated semi-conductor members show a high photosensitivity with a high dark resistance which closely approaches the photosensitivity of cadmium sulphide, in particular in the field of high radiation intensity. It is of particular advantage that the activation is a far less critical process than with compounds such as cadmium sulphide, and that the activation of these compounds, also with the use of a co-activator, is possible in an effective, simple and reproducible manner. This is probably possible owing to an automatic co-activation by the compound itself which may be considered a ternary compound built up from the binary compounds AX and B_2X_3 in equimolecular ratio. Neither in the case of an excess of AX, nor in the case of an excess of B_2X_3 did any deviation from the equimolecular ratio turn out to cause a decrease of the dark resistance or a deterioration of the photosensitivity which also benefits the reproducibility. The automatic co-activation may be explained as follows without restricting the invention to same: The said activator elements are probably incorporated monovalent in bivalent A-positions in the lattice and there compensated for by an automatic incorporation of an equal quantity of trivalent B-atoms, so that consequently each time two positions are occupied by a monovalent activator and a trivalent B. Any resulting surplus of A, e.g., cadmium which, in view of the low concentration of activators, will also be low, could remain in the lattice as a non-disturbing separate CdS-phase.

An additional important advantage of most of the compounds AB_2X_4 is that their melting temperature is relatively low and the decomposition pressure is not yet too large so that they can be melted in a simple manner in the commonly used quartz tubes. As a result of this, the activation can take place in a simple manner via the melt and said activation may be combined with the crystallization from the melt for the formation of crystals. For that purpose, purification methods and activation methods commonly used in the semiconductor technology may

be applied, in which, for example, a homogeneous distribution of the activator is effected by means of, for example, zone melting. As is usual with this type of compounds, the temperature treatments or melt treatments are carried out in an inert atmosphere or preferably in an atmosphere containing the volatile component of the compound so as to check decomposition. According to a further aspect of the invention, the activated semiconductor body may consequently consist of a crystallization product obtained from the melt. The said advantage holds in particular with respect to those compounds AB_2X_4 , in which B is formed by indium or gallium, such as for example $CdIn_2Te_4$, $CdIn_2S_4$, $ZnGa_2Se_4$, $ZnIn_2Se_4$. In connection with the satisfactory value of their band distance are particularly suitable those compounds in which B is formed by indium and X by sulphur or selenium, such, for example, as $ZnIn_2S_4$ and $CdIn_2S_4$. Particularly satisfactory results in every respect were already obtained with $CdIn_2S_4$. With this latter compound activated in the manner according to the invention, a low decay time, namely of the order of a millisecond, was obtained without more as a further advantage, which is more rapid by a factor 100 than in the case of cadmium sulphide. As far as the activators are concerned, gold and copper are preferred, since the best results are obtained with these substances.

In order that the invention may be readily carried into effect, it will now be described in greater detail, by way of examples and a drawing.

FIGURE 1 of the drawing shows schematically a photo-sensitive device according to the invention.

Example I

The compound $CdIn_2S_4$ was manufactured by mixing equimolecular quantities of CdS and In_2S_3 in powder form and heating in a H_2S -stream of atmospheric pressure at $900^\circ C$. for two hours. 1 cc. of a $10^{-2} N$ $Cu(NO_3)_2$ -solution was added to 4.70 g. of the thus obtained $CdIn_2S_4$ -powder. After mixing and drying at $70^\circ C$., the powder is heated in a quartz tube at $900^\circ C$., for approximately 60 minutes, while pure H_2S of atmospheric pressure is passed through the quartz tube. In this latter heating step the $Cu(NO_3)_2$ is converted into Cu_2S , the NO_2 and H_2O vapours arising from this reaction being carried away by the H_2S -stream. Then 100 mg. of sulphur are added to the powder and the whole is heated at $1150^\circ C$. for approximately 60 minutes in an evacuated sealed quartz tube of approximately 10 cc. capacity. The quantity of sulphur added effects a sulphur pressure of approximately 5 atm., and serves to check decomposition. Under the said circumstances, the preparation is in a melted state. After cooling, an activated crystallization product is obtained with a concentration of approximately 10^{-3} Cu-atoms per molecule of $CdIn_2S_4$. From this a strip-shaped member 11 (see figure) having a cross sectional area of approximately $2 \times 0.5 \text{ mm}^2$ is manufactured by sawing and after grinding and polishing it is attached at the ends by means of indium-amalgam 2 and 3 to two copper electrodes 4 and 5, so that the electrode distance amounts to approximately 4 mm. On measurement, the dark resistance between the electrodes turned out to be approximately 50M ohms. On irradiation with white light with an illumination intensity of approximately 10^4 lux, the resistance was only 500 ohms. Non-activated members of this compound, which otherwise were manufactured and provided with contacts in the same manner, turned out to have a dark resistance of substantially the same value, but the resistance with the same illumination with approximately 10^4 lux was considerably higher and amounted to approximately 10^5 ohms. The photosensitive member 1 with its electrodes 4 and 5 attached thereto may be used for instance in a circuit as shown further in the figure. A battery 6 and a load 7, which may for instance be a relay, are connected in series between the electrodes 4 and 5, while the light is directed on the member 1 between

the electrodes. The member 1 may in general consist of any of the compounds AB_2X_4 as described above, and doted with any of the elements Au, Ag and Cu.

For comparison, also members with other copper concentrations were manufactured and measured in otherwise the same manner. The dark resistance turned out to be each time of practically the same value, namely approximately 50M ohms, while the resistance when illuminated with 10^4 lux for the concentrations 10^{-2} , 5×10^{-3} , 2×10^{-3} , 5×10^{-4} and 10^{-4} amounted to 3×10^4 ohms, 9000 ohms, 500 ohms, 1000 ohms and 5000 ohms respectively.

When measuring the spectral sensitivity of these members, the maximum sensitivity turned out to be approximately 6000 A., while a good sensitivity occurred in the range of from 5500 A. to 7000 A.

It is noted that a superlinear dependence of the photocurrent with the illumination intensity was found in those cases in which the members are obtained from the crystallization product without further treatment. This superlinear behaviour may in many cases be removed substantially by grinding the members before providing them with contacts. In these cases, a substantially linear behaviour was found also in the case of a far lower illumination intensity. This disappearance of the superlinear dependence is probably linked up with the presence of an inhomogeneous distribution of centres in the member formed during the rather rapidly occurring crystallization from the melt.

Example II

Bodies from $CdIn_2S_4$, manufactured and treated in the same manner as described in Example I, with only this difference that silver was added as an activator, namely 1 cc. of a $10^{-2} N$ $AgNO_3$ -solution, showed a dark resistance of substantially the same value as mentioned above, while the resistance, when illuminated with 10^4 lux, was approximately 10^4 ohms.

Example III

Bodies from $CdIn_2S_4$, manufactured and treated in the same manner as described in Example I, with only this difference that as activator gold was added, namely 1 cc. of a $10^{-2} N$ $AuCl_3$ -solution, appeared to have a dark resistance of the same value as described above, while the resistance, when illuminated with 10^4 lux, only amounted to 300 ohms.

Example IV

Equimolecular quantities of ZnS and In_2S_3 were heated at $900^\circ C$. in an H_2S -stream of atmospheric pressure for approximately two hours so as to form the compound $ZnIn_2S_4$. 1 cc. of $10^{-2} N$ $Cu(NO_3)_2$ -solution was added to 4.2 g. of the thus obtained $ZnIn_2S_4$ -powder. After mixing and drying at $70^\circ C$., the powder is heated in a quartz tube at $900^\circ C$. for approximately sixty minutes in a pure H_2S -stream of atmospheric pressure. Then 100 mg. of sulphur are added and the whole is heated at $1200^\circ C$. for approximately sixty minutes in an evacuated sealed quartz tube of approximately 10 cc. capacity. The preparation is then in the melted state. After cooling, a crystallization product is obtained containing approximately 10^{-3} Cu per mol $ZnIn_2S_4$. From this, bodies are manufactured and provided with contacts in the same manner as described in Example I. The dark resistance turned out to be approximately 100M ohms, while, when illuminating with white light and at an intensity of approximately 10^4 lux, the resistance amounted to only 1000 ohms.

Example V

The compound $ZnGa_2S_4$ was manufactured by heating equimolecular quantities of ZnS and Ga_2S_3 in powder form at $1000^\circ C$. for approximately two hours in an H_2S -stream of atmospheric pressure. 10 cc. of a $10^{-2} N$ $Mn(NO_3)_2$ -solution and 1 cc. of a $10^{-2} N$ $Cu(NO_3)_2$ -solution were added to 3.3 g. of this powder. After mixing and drying at $70^\circ C$., the powder is heated at $1150^\circ C$.

C., which is below the melting point of $ZnGa_2S_4$, for two hours in a quartz tube through which H_2S of atmospheric pressure is passed. The thus obtained powder is washed with a $Cu(NO_3)_2$ -solution in order to obtain small amounts of non-incorporated copper-sulphide at the surface of $ZnGa_2S_4$ -grains. After drying, the powder is provided between two electrodes, one of which is transparent and consists, for example, of glass which has been made conductive, and the other of copper. When setting up a direct or alternating voltage, a red electro-luminescence occurs, the maximum of which lies at approximately 6500 Å. The emission originated from the manganese centres, while the presence of the activator copper turned out to intensify the emission.

What is claimed is:

1. A method of making a photosensitive body constituted substantially of the activated compound AB_2X_4 , where A is selected from the group consisting of zinc and cadmium, B is selected from the group consisting of indium, gallium and aluminum, and X is selected from the group consisting of sulphur, selenium and tellurium, comprising forming a melt of the said compound and a monovalent activator selected from the group consisting of gold, silver and copper, crystallizing from the melt the said activated compound, and forming a coherent body of crystals of the said activated compound.

2. A method of making a photosensitive body constituted substantially of the activated compound AB_2X_4 , where A is selected from the group consisting of zinc and cadmium, B is selected from the group consisting of indium, gallium and aluminum, and X is selected from the group consisting of sulphur, selenium and tellurium, comprising forming a melt of the said compound and about 10^{-5} to 10^{-2} atoms per mole of the compound of a monovalent activator selected from the group consisting of gold, silver and copper crystallizing from the melt the said activated compound, and forming a body of the said activated compound.

3. The method of claim 2 wherein the compound is $CdIn_2S_4$.

4. A semiconductor device comprising a photosensitive body consisting essentially of the composition AB_2X_4 , wherein A is at least one element selected from the group consisting of zinc and cadmium, B is at least one element

selected from the group consisting of indium, gallium and aluminum, and X is at least one element selected from the group consisting of sulphur, selenium and tellurium, said composition including as an essential activator between approximately 10^{-5} and 10^{-2} atoms of at least one element selected from the group consisting of gold, silver and copper per molecule of the composition, and spaced electrode connections to said body.

5. A photosensitive semiconductor device comprising a crystallization product having a composition consisting essentially of AB_2X_4 , wherein A is at least one element selected from the group consisting of zinc and cadmium, B is at least one element selected from the group consisting of indium, gallium and aluminum, and X is at least one element selected from the group consisting of sulphur, selenium and tellurium, and activated substantially only by about 10^{-5} to 10^{-2} atoms of an element selected from the group consisting of gold, silver and copper per molecule of the composition, and electrode connections to said body.

6. A semiconductor device comprising a crystalline body consisting essentially of the composition $CdIn_2S_4$ activated substantially only by about 10^{-4} to 10^{-3} atoms per molecule of $CdIn_2S_4$ of gold.

7. A semiconductor device comprising a crystalline body consisting essentially of the composition $CdIn_2S_4$ activated substantially only by about 10^{-4} to 10^{-3} atoms per molecule of $CdIn_2S_4$ of copper.
